United States Patent Office.

J. A. MINER AND H. J. TORREY, OF WELLSVILLE, NEW YORK.

Letters Patent No. 90,459, dated May 25, 1869.

STOVE-PIPE SHELF AND OVEN.

The Schedule referred to in these Letters Patent and making part of the same.

To all whom it may concern:

Be it known that we, J. A. MINER, and H. J. TORREY, of Wellsville, in the county of Allegany, and State of New York, have invented a new and improved Stove-Pipe Shelf and Oven; and we do hereby declare that the following is a full, clear, and exact description thereof, which will enable others skilled in the art to make and use the same, reference being had to the accompanying drawings, forming part of this specification.

The object of this invention is to provide a stove-pipe shelf and oven, or cover, for use with cooking-stoves, for keeping articles warm, and so arranged that the shelf may be readily attached to or detached from the pipe, and be rotated thereon if required.

Figure 1 represents an elevation of our improvement partly in section, and

Figure 2 represents a plan of the bottom of the shelf.

Similar letters of reference indicate corresponding parts.

To make a circular shelf, we cast two semicircular plates, A B, with central semicircular recesses, forming, when the plates are joined, a hole for the pipe.

To connect these plates, we make, on the lower side of the part B, hooks C, by casting them together with the plates, so formed as to project from under the radial edge and engage with rounded projections C, correspondingly arranged on the other part A, and on this part we form, in a similar way, lugs D, which project under the edges of the part B. These hooks and projections serve, when the two parts of the shelf are connected around the pipe and supported around the central hole by a collar E, to support both parts of the shelf in a horizontal position, and to prevent their being separated laterally.

The collar E may be connected to the pipe in two

parts having vertical extensions F, to give a firm bearing, and clamping-ears G, for connection by pins or bolts, so as to clamp them to the pipe, to hold at any point by friction.

The parts A and B of the shelf are placed in position, or removed therefrom, by lifting the outer edges in a manner to turn the hooks C around the lugs C, similar to the operation of a hinge-joint, which permits the connection or disconnection of the parts when sufficiently turned.

H represents hooks, which may be made on the shelf for holding any articles it may be desirable to hang thereon.

I represents a sheet-metal oven or cover, fitted to set on the shelf and enclose the articles placed thereon to be kept warm.

Having thus described our invention,

What we claim as new, and desire to secure by Letters Patent, is—

1. A stove-pipe shelf, composed of the two parts A B, and provided with the hooks C, lugs D, and the central recesses, all substantially as specified.
2. The combination with a shelf, constructed as described, of the cover I, substantially as specified.
3. The combination with the shelf, constructed as described, of the sectional collars E, arranged as specified.

The above specification of our invention signed by us, these 6th and 7th days of April, 1869.

J. A. MINER.
H. J. TORREY.
